Primary Examiner — Clint A Samuel

(57) **CLAIM**

The ornamental design for desk lamp, substantially as shown and described.

DESCRIPTION

FIG. 1 is a front perspective view of desk lamp, showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines in the drawings illustrate the portions of the desk lamp that form no part of the claimed design.

The part of the drawings shown in a coarse dot pattern, along with the broken-line perimeter illustrates portions of the desk lamp that forms no part of the claimed design.

1 Claim, 7 Drawing Sheets(56)
